UNITED STATES PATENT OFFICE.

JAMES W. CONNERY, OF PHILADELPHIA, PENNSYLVANIA.

STEAM-BOILER.

SPECIFICATION forming part of Letters Patent No. 349,568, dated September 21, 1886.

Application filed July 20, 1886. Serial No. 208,519. (No model.)

To all whom it may concern:

Be it known that I, JAMES W. CONNERY, a citizen of the United States, residing at Philadelphia, in the county of Philadelphia and State of Pennsylvania, have invented certain new and useful Improvements in Steam-Boilers, of which the following is a full, clear, and exact description.

The objects of this invention are to provide vertical or upright steam boilers or generators with greater water-space and larger evaporating-surface; also, to facilitate the access to the flues for cleaning and repairs, and also to utilize the heat more effectually than is common in this class of boilers.

The invention consists in an upright steam-boiler having an upper section combining the functions of boiler and steam-dome, it being connected with the water-space of the boiler proper by passages of less diameter than its evaporating-area, and to this end being spherical or globular, or partly so, or of the shape of an inverted truncated cone, said section being also removable.

The invention also consists in interposing between the smoke-stack and crown or flue sheet a revoluble casing provided with a door, whereby access may be had to the interior of the smoke-chamber surrounding the upper section of the boiler for repairs, cleaning, and the like.

The invention also consists in the construction and arrangement of the steam outlet or service pipes, whereby they are not disturbed in getting at the flues or other inner parts.

The invention also consists in a certain deflecting medium for throwing the heat upon the upper steam generating and containing section.

In the accompanying drawings, in the several figures of which like parts are similarly designated, Figure 1 is a partly top and partly sectional plan view; Fig. 2, a similar elevation; and Fig. 3 is a similar elevation of another form of upper section or head.

The fire-box *a*, jacket *b*, water-space *c*, and fire-flues *d* therein may be of usual construction and arrangement, substantially as shown. The flue or crown sheet *e* has a central opening, *f*, over which is secured the boiler section or head *g*. The base of this section is provided with a flange, *h*, through which bolts *i*

are passed to secure it to the flue-sheet around the opening *f*, and so that it may be readily removed for repairs, cleaning, &c. This section *g*, which, as will presently appear, serves the purposes of a generator and steam-dome, is of increasing diameter from its plane of connection with the flue-sheet upward, and to this end may be trunco-conical, as in Fig. 2, 55 or globular or spherical, as in Fig. 3. The section *g* and water-space *c* are further connected by pipes *j*, the said pipes opening into said section at or near its greatest diameter. These pipes, with the opening *f*, insure a 60 thorough circulation of the water through the water-space and section, and insure the constant submersion of the fire-flues. It will be observed that the water stands in the section *g* on or about on a level with the openings thereto of the pipes *j*, whereby is gained a large evaporating-surface. Above such water-level the section affords a steam-dome. The pipes *j* in the spherical section 70 are preferably curved, so as to make a good 75 joint with the section. Plates (one or more) *k* are disposed around the section at an inclination thereto, so as to deflect the heat upon the section, and these deflector-plates are bolted to the flue-sheet, substantially as 80 shown in Fig. 2. The stack-base *l* is supported upon the section *g* by means of the flanged columns *m*, which latter are affixed to the said section, and the said columns serve to receive the steam outlet or service pipes *o*. 85

Between the flue-sheet and the stack-base is arranged a revoluble shell, *p*, having a door, *q*, provided with a hand-grip, *r*. The door is readily removable to gain access to the interior of the smoke-chamber, and the shell *p* 90 is revoluble, so as to bring the doorway to any and all portions of the boiler. I deem it essential to have the lower portion of the section *g* angular or curvilinear, so as to avoid the dangers incident to a flat crown-sheet when 95 in close proximity to the water-line and direct action of the products of combustion. The section *g* is in capacity about equal to one-third of the capacity of the water-space. The section or head *g* may be further secured 100 by a stay bolt or rod, *s*, passing through it and anchored to the head of the fire-box.

The drawings indicate the use of four pipes, *j*, and also three service-pipes, *o*; but obviously

these numbers may be increased or diminished at pleasure.

What I claim is—

1. An upright steam-boiler having an upper section connected with the water-space by a series of passages, *f j*, and increasing in diameter as it rises from the flue-sheet, and combining the functions of a steam-generator and steam-dome, substantially as described.
2. In a vertical steam-generator having a water-space, the combined steam generator and dome connected with said water-space at its foot, and also at points on or about on a level with its greatest diameter above said foot, and of increasing diameter upward from said foot, and having suitable steam-outlets, substantially as described.
3. A vertical steam-generator provided with section *g*, shaped substantially as shown, and secured to the flue-sheet by a flange and bolts, combined with detachable pipes *j*, substantially as described.
4. In a vertical steam generator or boiler,

the combination, with the jacket of the boiler and the stack-base, of a revoluble casing provided with an inlet, whereby access may be had to the interior of the smoke-chamber, substantially as described.

5. In a steam-generator, a stack-base, through which the service-pipes are passed, combined with hollow columns, upon which said stack-base is supported independent of the jacket of the boiler, substantially as described.

6. In a vertical steam generator or boiler provided with a section, *g*, deflecting plate or plates *k*, secured to the flue-sheet and inclined toward the said section, substantially as described.

In testimony whereof I have hereunto set my hand this 17th day of July, A. D. 1886.

JAMES W. CONNERY.
